UNITED STATES PATENT OFFICE.

JACOB J. BUSENBENZ, OF CHICAGO, ILLINOIS, ASSIGNOR TO DIFFERENTIAL POWER CLOCK COMPANY, OF CHICAGO, ILLINOIS, A CORPORATION OF ILLINOIS.

CLOCK.

1,012,243.

Specification of Letters Patent. Patented Dec. 19, 1911.

Application filed May 2, 1911. Serial No. 624,630.

To all whom it may concern:

Be it known that I, JACOB J. BUSENBENZ, a citizen of the United States, residing at Chicago, in the county of Cook and State 5 of Illinois, have invented a new and useful Improvement in Clocks, of which the following is a specification.

My invention relates to an improvement on the long-period clock which forms the 10 subject of United States Letters Patent No. 973,854, granted to me October 25th, 1910; and it is in the nature of a modification of the construction shown and described in said Letters Patent.

15 In the accompanying drawings, Figure 1 is a broken view in sectional elevation of a clock embodying my improvement; Fig. 2 is an enlarged broken sectional view of the modified train-driving spring device, and 20 Fig. 3 is a section on line 3, Fig. 2.

With the exception of the spring-device, the parts may be substantially identical with those of my aforesaid patent, though 25 they are shown somewhat differently arranged in the present embodiment of the invention. Thus, the case 3 contains, in a frame 4 at the side thereof equipped with the glass-covered dial 5, the stored-power motor, in the form of two similar flat-spring coils 6 and 7 carrying corresponding gears 8 and 9 meshing with an interposed pinion 10 and adapted to be wound at key-arbors 11, 11, through the dial; and detent-mechanism 12 is provided on each spring. 35 The clock-train 13 turns shafts 14 and 15, as usual, carrying, respectively, the hour and minute hands 16 and 17.

From a horizontal shelf 18 supported in the case rises a post 19 terminating in a 40 barrel-like support 20 for a horizontal cylindrical tube 21 which contains near the end adjacent to the frame 4 a diametrically-reduced section 22, the tube being fastened against movement in its support, as by a pin 23. A stud 24 is rigidly fastened to a support 25 on the front side of the case to extend horizontally and aline with the longitudinal center of the adjacent end of the tube 21, and on this stud is rotatably 45 mounted a sleeve 26 having the pinion 10 formed upon it between its ends. A similar stud 27 is rigidly fastened to the back of the case and has rotatably mounted upon it a sleeve 28 like the sleeve 26 and carrying a 50 gear-wheel 29 meshing with the first gear of

the train 13. In the tube is confined a spiral spring 30, into the opposite ends of which the inner ends of the sleeves 26 and 28 respectively extend to center the spring. One end of the spring is fastened to the pinion 10 and its other end is fastened to the gear 29, as shown in Fig. 2.

With the motor-springs 6 and 7 wound up, they coöperate by their recoil-force in gradually unwinding, which may continue 65 for a year or more, to continuously turn the pinion 10 in one direction and thereby constantly tension the spring 30 throughout its length by expanding it from its normal condition until further expansion is arrested 70 by engagement of a section of the spring with the constricted tube-section 22. As this tensioning-action of the pinion against one end of the spring 30 proceeds, only so much driving power is generated in the 75 spring by expanding it as the limit of its expansion in the tube-section 22 will permit, which tensions the opposite, driving-end of the spring just sufficiently to overcome the resistance of the clock-train and 80 drive it.

It will be observed that the spring-action in the present case is a mere reversal of that in the embodiment of my invention shown and described in said patent, involving, as 85 it does, tensioning the spring by expanding it against a stop surrounding a section thereof, instead of contracting the spring about a stop within a section thereof, as in that patent. In both instances the power 90 initially exerted by the primary motor is abnormally great—say several hundred pounds—and as the motor-springs run down the power becomes less and less until it is 95 nil, but meantime, so long as any power is left in the motor, it must be sufficient to drive the clock-train; the spiral spring can not be tensioned, whatever the power exerted upon it by the primary motor, in excess of what the stop-medium will permit, 100 and the minimum power exerted by the motor will tension the spring to that extent, so that the train-driving end-section of the spring is always at the same tension and actuates the clock-train uniformly, causing 105 perfect time-keeping of the clock.

What I claim, as new and desire to secure by Letters Patent is:

1. In a clock of the character described, the combination with a primary motor and 110

a clock-train, of a spiral spring having one end geared to the motor for expanding the spring and its opposite end geared to the train to drive it by the power of such expansion, and a stop about the spring to limit the extent of its expansion by the motor, for the purpose set forth.

2. In a clock of the character described, the combination with a primary motor and a clock-train, of a pinion driven by said motor, a cylindrical tube extending between the pinion and train, and provided with a contracted section, and a spiral spring in said tube having its ends connected respectively with said pinion and train, for the purpose set forth.

3. In a clock of the character described,

the combination with a primary motor and a clock-train, of a tube-support between said motor and train, a cylindrical tube confined in said support and provided with a contracted section, sleeves rotatably mounted on studs at the opposite ends of the tube and carrying, respectively, a pinion geared to said motor and a gear-wheel for driving said train, and a spiral spring confined in the tube and having one end connected with said pinion and its other end connected with said gear-wheel, for the purpose set forth.

JACOB J. BUSENBENZ.

In presence of—

RALPH SCHAEFER,
JOHN WILSON.
